(57) **CLAIM**

The ornamental design for a sniper, as shown.

DESCRIPTION

FIG. 1 is a front elevation view of a sniper showing my new design;

FIG. 2 is a rear elevation view;

FIG. 3 is a top plan view;

FIG. 4 is a left side elevation view;

FIG. 5 is a right side elevation view; and,

FIG. 6 is a perspective view thereof.

My tool is $5\frac{3}{4}'' \times 1\frac{1}{2}''$ cylindrical aluminum with two levels and one laser.
